CARL C. RIOTTE AND EUGENE A. RIOTTE, OF NEW YORK, N. Y.

SPARKING-IGNITER MECHANISM.

SPECIFICATION forming part of Letters Patent No. 758,217, dated April 26, 1904.

Application filed April 15, 1901. Serial No. 55,860. (No model.)

To all whom it may concern:

Be it known that we, CARL C. RIOTTE and EUGENE A. RIOTTE, citizens of the United States, residing in the borough of Manhattan, 5 city, county, and State of New York, have jointly invented certain new and useful Improvements in Sparking-Igniter Mechanism, of which the following is a specification:

Our invention aims to provide an igniter mechanism for explosion-engines and the like in which are combined various features of improvement, as specified in the claims herein-after.

Referring to the accompanying drawings, 15 showing one embodiment of our invention, Figure 1 is an end elevation of our apparatus as applied to a four-cylinder engine. Fig. 2 is a side elevation of the same. Fig. 3 is a horizontal section on the line 3 3 of Fig. 2. Fig. 20 4 is a diagram showing the operation of the adjusting-rod. Fig. 5 is a side elevation, partly in section, showing the feature of our invention which is adapted to single igniters. Figs. 6 and 7 are fragmentary sections showing 25 different positions of the igniter-arm with reference to the operating member.

Referring to the drawings, A represents the cylinders of any suitable multiple-cylinder engine, of which B is the base, C the crank-shaft chamber, and D the crank-shaft, all these parts being of well-known construction.

In the operation of explosion-engines the timing of the ignition and the consequent explosion is dependent upon the speed of the engine. At high speeds the ignition should occur before the crank reaches the dead-center. As the speed is slowed, however, in order to prevent the force of the explosion from causing the engine to kick back the ignition should 35 be delayed, and at very slow speeds it is advisable to operate the igniter an instant after the crank passes the dead-center. The adjustment of the igniters for the various speeds of the engine is a matter requiring considerable care. For a multiple-cylinder engine the igniters of each of the cylinders should be simultaneously advanced or retarded to secure even working of the engine and to insure against kicking back, and during operation 45 50 they should remain immovable in correspond-

ing positions of adjustment relatively to each other. To adjust each of the igniters separately requires considerable delay and does not insure that each shall be adjusted exactly equally, so as to precede or follow the moment of dead-center by an equal amount or that they shall remain so and immovable relatively to each other. According to one feature of our invention we provide a very simple mechanism whereby the timing of the several igniters is varied simultaneously and by exactly equal amounts. For this purpose we preferably operate the igniters by means of a series of cams which operate a corresponding series of igniter-rods, the means for transmitting the motion of the cams to the igniter-rods being adjustable and being connected immovably to each other, as by means of a single operating member arranged for hand operation or otherwise, and also arranged to be frictionally held passive in any position of adjustment in which it may be moved by hand or by the kicking back of the cam, or otherwise.

An example of such mechanism is shown in 75 Figs. 1, 2, and 3. Driven from the crank-shaft D of the engine by any suitable transmitting mechanism, such as the gearing E, is a cam-shaft F, on which is a series of cams G¹, G², &c., one for each igniter mechanism, and arranged in such angular relation to each other as to give the proper relative time of ignition for the several cylinders. The cams operate at each revolution of the cam-shaft F to lift each igniter-rod H to operate its igniter, which 80 we designate as a whole by the letter J. In order to vary the time at which the rod H will be lifted by its cam, we provide a means for transmitting the movement of the cam to the rod, which means is adjustable in position and preferably consists of a rod K, provided with a shouldered lug L on its face in contact with the cam, and we provide for the movement of the rod K, so that the lug L shall be released from its cam at an earlier or 85 later instant, as desired.

In order that all of the adjusting-rods K shall be moved simultaneously and an equal distance, they are connected to any common operating member, such as the shaft M, by 90 95 100

means of arms N thereon. The shaft M is provided also with one or more operating-arms O, which may be operated directly by the handle P or by any other suitable means. 5 The arm O bears with considerable friction against a friction-plate R, which is shown as mounted on the end of the cylinders and which may or may not be provided with an index-scale S to show the time of operation 10 of the igniter with respect to the position of the crank.

In an engine of the type shown our mechanism is conveniently arranged by mounting the cam-shaft on the same side of the engine 15 with the igniters, so that a single straight rod H is used to convey the movement of the cam to the igniter-arm. The shaft M may be arranged on the opposite side of the engine supported in bearings T on the portions B' of 20 the casing. The adjusting-rods K may thus pass through the spaces B² between the portions B' of the casing. The operating-arm O of the shaft M may be at any convenient point other than at the end of the shaft, as shown 25 in Fig. 2.

Those parts of the mechanism which have no relation to our invention are omitted from the drawings for the sake of clearness. In order to prevent the dropping of the lug L 30 of the adjusting-rod K on the cam and the wearing away of these parts, we preferably provide lugs U, upon which the rods K fall when they are released by the cams. These lugs, as shown, may be directly on the frame 35 inside the openings B².

When the engine is slowed down and it becomes necessary to retard the ignition, the arm O is thrown in the direction of the arrow, Fig. 1, which throws the adjusting-rod K to 40 the left—as, for example, to the dotted-line position in Fig. 4—whereby instead of dropping when the cam reaches the position shown it will be held an instant longer. By the arrangement shown there is obviously very little 45 strain on the adjusting-rod, so as to throw it out of adjustment, and whatever accidental strains come upon it are resisted by the frictional contact between the arm O and the friction member R.

50 By our invention we also simplify the construction of the igniter and provide a very efficient means for giving it the desired operation. For this purpose we provide the igniter with an arm on the outside of the ignition-chamber, which is operated by a reciprocating member—such as the rod H, above referred to—and we provide also a means whereby the arm is held in its normal position by a yielding stop, which acts to maintain the arm 55 always at a determined angle with the operating member, though permitting a departure from said angle under circumstances hereinafter explained. Consequently when the operating member is reciprocated and the normal 60 angle of the arm and the operating member 65

is departed from the strain on the yielding stop (as soon as the operating member is released by its cam) brings the arm again to its normal position and by its momentum past such position, so as to make a sudden and 70 wide gap for the spark. The yielding member then restores the arm to its normal position by means of its elasticity. This feature of our invention is shown in Figs. 5, 6, and 7 and in the form shown is especially adapted 75 for operation with the improved adjusting means described, since it is readily connected to such adjusting means and since the yielding stop is directly on the rod H. The arm V of the igniter is held by a pair of stops on the rod H, one of which, preferably the upper, is a fixed stop consisting of a washer W, held in place, as by nuts X, and having a flat face adapted to bear on the face of the arm. The yielding stop, which for vertical engines 80 is preferably arranged on the under side of the arm, may consist of a spiral spring Y, held up by means of a nut Z. The igniter-operating rod H preferably passes through a flared opening a in the arm V. The pressure 85 of the spring Y, pressing the arm against the flat face of the stop W, tends to maintain the rod in its normal position, and the strength of the spring is such as to adapt it to return the rod to such normal position after it has 90 been moved therefrom. With this construction the rod may be made very light, so as to be easily lifted by the spring and so as to operate with a minimum amount of shock and of wear upon the parts. The normal position, 95 Fig. 5, of said igniter-operating rod H is intermediate the extreme positions to which it is raised and lowered. It does not touch the adjusting-rod K except when the latter is raised by the cam and at the first downward 100 movement after the cam releases the rod K, during which downward movement the rod H moves downward under the momentum of the forces hereinafter described to make an abnormally wide opening between the spark-terminals. 105

When the cam G' operates to lift the rod H, the parts assume the position of Fig. 6. The spring Y is compressed, because of the angular position of the faces of the arm V and because the points of the igniter are in contact. This movement occurs while the lug L is riding on the higher part of the cam G' and presses the points of the igniter into good 110 spring contact. When the rod H is released, the expansion of the spring Y brings the arm V to its normal horizontal position and by its momentum past said position to that of Fig. 7 with considerable speed. The pressure of the spring and its rapidity of action are controlled 115 by adjusting the nut Z on the rod. After the spark the same spring Y will again act to bring the parts to their normal position by reason of its pressure acting against the arm with a leverage due to the angular position of the arm 120 125 130

relatively to the flat face of the washer W and the distance from the center of pressure of the spring to the inner bearing edge of the washer. By this arrangement of the spring

5 Y, therefore, we make one element serve for pressing the points together, separating them widely and quickly and returning them to their normal position, and we also reduce considerably the shock of the parts.

10 It will be obvious to those skilled in the art that our invention may be variously availed of and may be considerably modified in the details and arrangements of the parts. It will be understood, therefore, that we do not 15 limit ourselves to the specific embodiment of our invention shown and described, but desire to cover all igniter mechanism embodying the substantial principle of the invention.

10 What we claim, therefore, and desire to secure by Letters Patent, are the following-defined novel features, each substantially as described:

20 1. The combination with an igniter, of a cam for operating the same, transmitting mechanism between said cam and igniter, and an operating-arm O for moving said transmitting mechanism adapted to bear normally automatically and in all positions against a friction-plate R for holding said transmitting 25 mechanism passive in any position to which it is moved and for permitting it to yield in case of backward movement of said cam.

20 2. The combination with an igniter, of a cam for operating the same, means for transmitting the motion of said cam to said igniter, said means being movable radially of the axis of the cam and being also movable laterally of the axis of the cam and transversely of such radial movement, and an operating-arm 35 O for moving said transmitting mechanism

adapted to bear normally automatically and in all positions against a friction-plate R for holding said transmitting mechanism passive in any position to which it is moved and for permitting it to yield in case of backward 45 movement of said cam.

3. The combination of a plurality of igniters, cams for operating the same, transmitting mechanisms between said cams and igniters, and a single operating-arm O for moving 50 said transmitting mechanisms simultaneously and adapted to bear normally automatically and in all positions against a friction-plate R for holding said transmitting mechanisms passive in any position to which they are moved 55 and permitting them to yield in case of backward movement of said cams.

4. The combination of a plurality of igniters, operating-cams therefor, igniter-rods H, adjusting-rods K between said cams and igniter-rods, a shaft M having arms N connected to said adjusting-rods and having an operating-arm O mounted to bear normally, automatically and in all positions, against a friction-plate R for holding said shaft M in any 60 desired position, whereby the time of operation of said igniters may be varied simultaneously and said igniters may be held in corresponding positions of adjustment and immovable relatively to each other but so as to yield 65 together in case of backward movement of said cams.

In witness whereof we have hereunto signed our names in the presence of two subscribing witnesses.
